(57) **CLAIM**

The ornamental design for a grooved beverage locking device, as shown and described.

DESCRIPTION

FIG. 1 is a perspective view of a grooved beverage locking device.

FIG. 2 is a side view of the grooved beverage locking device.

FIG. 3 is a top view of the grooved beverage locking device.

FIG. 4 is an end view of the grooved beverage locking device.

FIG. 5 is an opposite end view relative to FIG. 4 of the grooved beverage locking device; and,

FIG. 6 is a perspective view of the grooved locking device engaged with a bottle cap and bottle for environmental illustration.
